US00D641078S

(12) **United States Design Patent**
Morgan et al.

(10) **Patent No.:** **US D641,078 S**
(45) **Date of Patent:** **** Jul. 5, 2011**

(54) **MEDICAL SYRINGE WITH NEEDLE TIP CAP**

(75) Inventors: **Darrell P. Morgan**, Sonning Common (GB); **Alex Lee**, New York, NY (US); **Dan Formosa**, Piermont, NY (US); **Steven Vordenberg**, Amherst, NH (US); **Joern Vicari**, Brooklyn, NY (US); **Boris Kontorovich**, Brooklyn, NY (US); **Eric Freitag**, New York, NY (US)

(73) Assignee: **UCB Pharma, S.A.**, Brussels (BE)

(**) Term: **14 Years**

(21) Appl. No.: **29/313,356**

(22) Filed: **Dec. 29, 2008**

(51) **LOC (9) Cl.** **24-02**

(52) **U.S. Cl.** **D24/114**

(58) **Field of Classification Search** **D24/112, D24/113, 114, 127, 130, 133, 144, 152; 433/80; 604/93.01, 93.02, 158, 163, 164.08, 181, 604/187, 192, 198, 185, 227, 232; 606/263**
See application file for complete search history.

(74) *Attorney, Agent, or Firm* — Ropes & Gray LLP

(57) **CLAIM**

The ornamental design for a medical syringe with needle tip cap, as shown and described.

DESCRIPTION

FIG. 1 is a perspective view of a medical syringe with needle tip cap.

FIG. 2 is a top view of a medical syringe with needle tip cap.

FIG. 3 is a left side elevational view of a medical syringe with needle tip cap.

FIG. 4 is a front elevational view of a medical syringe with needle tip cap.

FIG. 5 is a right side elevational view of a medical syringe with needle tip cap.

FIG. 6 is a back view of a medical syringe with needle tip cap.

FIG. 7 is a bottom view of a medical syringe with needle tip cap; and,

FIG. 8 is an exploded view of a medical syringe with needle tip cap.

1 Claim, 4 Drawing Sheets
